UNITED STATES PATENT OFFICE.

CHARLES J. MARTH, OF ST. LOUIS, MISSOURI, ASSIGNOR TO WAYNE MANUFACTURING COMPANY, OF ST. LOUIS, MISSOURI, A CORPORATION OF MISSOURI.

OPERATING MECHANISM FOR WASHING-MACHINES.

1,181,329.

Specification of Letters Patent.

Patented May 2, 1916.

Application filed February 25, 1915. Serial No. 10,629.

To all whom it may concern:

Be it known that I, CHARLES J. MARTH, a citizen of the United States, residing at the city of St. Louis and State of Missouri, have invented a new and useful Operating Mechanism for Washing-Machines, of which the following is a specification.

This invention relates to washing machines and consists in the novel design, arrangement and combination of parts herein-after fully disclosed.

An object of the invention is to provide a washing machine comprising a tub or receptacle wherein an agitator of novel design 15 is operatively mounted in combination with means for reciprocating the agitator.

Specific objects and advantages to be obtained from the use of the construction of the present invention will readily appear to 20 those skilled in the art without specific mention, from the following detailed description thereof in which reference is made to the accompanying drawings and in which—

Figure 1 is a top plan view of a washing 25 machine embodying my invention the cover of the tub being removed. Fig. 2 is a bottom plan view of the washing machine. Fig. 3 is a side elevation of the washing machine a portion of the tub being broken away to 30 more fully disclose the interior arrangement of the agitator and associated parts. Fig. 4 is a cross sectional view taken substantially on the line 4—4 of Fig. 3. Fig. 5 is a cross sectional view taken on the line 5—5 of Fig. 35. Fig. 6 is a side view of the washing machine substantially from a point at a right-angle from the view illustrated in Fig. 3. Fig. 7 is a plan of the upper end of the agitator connected to the agitator shaft, with a 40 portion of the cover and closure surrounding the agitator head. Fig. 8 is a vertical section through the same connection as is illustrated in Fig. 7, and Fig. 9 is a plan view, the head of the agitator with certain 45 parts removed.

In the embodiment illustrated in the drawings I have shown a tub 1 supported by standards or legs 2, the tub being sufficiently elevated above the floor to accommodate the 50 driving mechanism which is supported below the tub. The tub is provided with a removable cover or lid 3, said cover or lid being provided with an opening 4 through which the upper end of the agitator and agitator shaft project. Supported upon the

upper face of the cover or lid encircling the opening 4 is a ring 5. A closure comprising matching segmental plates 5^a are pivoted on said ring and are adapted to be latched about the extending end of the agitator, to 60 close the space between the same and the walls for the opening 4 when the parts are adjusted.

A tubular standard 6 is supported within the tub 1 in an upright position substantially at the center of the tub; said standard being bolted to or otherwise engaged with the bottom of the tub in the manner clearly illustrated in Fig. 3 of the drawing. An agitator shaft 7 is slidably mounted within 70 the standard 6 and is of a sufficient length so that it extends above the upper and below the lower end of the standard through an opening in the bottom wall of the tub. The lower end of the shaft 7 which projects 75 through the bottom of the tub is guided and supported by a bracket 8 which is provided with passage-ways or openings 9 and 10, respectively, for the shaft 7. The upper end of the shaft 7 is threaded to receive the connecting element of the agitator, as will be more fully explained hereinafter.

The agitator element which is releasably mounted upon the agitator shaft 7 is of novel construction and design and comprises 85 a hub element 11 in the form of a hollow cylinder from the lower end of which extend spaced obliquely extending legs 12, which support at the lower ends an annular plate 14. The interior diameter of the hub 90 member 11 is such that when in position it will fit over the upper end of the standard 6, so that when the agitator shaft is reciprocated the agitator will be held in proper adjustment and guided in its reciprocating action so that it may move up and down in a path true to its axis. A hood or cup 15 is conical in form and is bolted to the plate 14 in the manner clearly illustrated in Fig. 3 of the drawing, by reference to which it will be seen that the small end of said hood or cup is secured to the lower face of the annular plate 14, the bolts passing through an inturned flange formed at the upper end of said hood and through 100 said plate. A circular plate 16 is mounted in a horizontal position at the top of the hood or cup 15 and is held in position between the inturned flange and the plate 14 it being clamped therebetween, as clearly 110

shown in Fig. 3 of the drawings. The plate 16 extends beyond the upper edge of the hood or cup for some distance and serves the function of preventing the clothes in the tub from packing against the outer sloping walls of the hood and also prevents the streams of water ejected from the perforations in the walls of the hood, when the hood is depressed, from splashing against the upper part of the tub.

10 The agitator is adapted to be releasably connected to the agitator shaft. In the embodiment of the invention illustrated in the drawing the releasable connection comprises 15 a nut 17 interiorly threaded and adapted to be screwed upon the threaded end of the agitator shaft. The nut 17 is provided with an enlarged lower portion 17^a which is adapted to seat in a recess formed in the 20 upper face of the hub element 11 and to be retained in position by segmental plates 18, which are held in position by screws passing therethrough and into the upper face of the hub member as illustrated in Fig. 9 in 25 which one of the plates 18 is shown in position and the other removed. In order to facilitate the adjustment of the nut over the end of the agitator shaft an engageable portion or hand hold 17^b is provided.

30 The hub element 11 a slight distance below the head thereof, is provided with offset portions 13 which are cut through to the inner part of the hub, as clearly illustrated in Fig. 8. This construction admits air to 35 the inner portion of the hub element and prevents a vacuum being created in the hub which would draw the water over the edge of the standard 6 causing leakage through the bottom of the tub. It will be noted also that 40 there are spaces or passage ways between the legs 12 for the exit of the water that is forced around the standard 6 between it and the walls of the opening through the plate 14, the plate 16 and the opening in the hood 15. 45 In practice it has been found that the inrush of the water at this point is considerable on the depression of the agitator and unless exit means therefor be provided it will form a cushion in the interior of the hub and also 50 force water downwardly in the standard and out through the bottom of the tub, and it is to overcome this disadvantage that the space between the legs 12 and the openings 13 have been provided.

55 In operation the tub, as will be understood, is first supplied with water and the clothes to be washed placed therein and the agitator then placed in position upon the agitator shaft and the releasable connection 60 adjusted to coöperatively connect the shaft with the agitator, and the cover then placed in position and the closure 5^a locked about the hub 11 of the agitator. As the agitator shaft 7 is reciprocated in an up and down 65 path of movement, the agitator upon its

downward movement into the water and against the clothes compresses a volume of air within the hood or cup, forcing the same through the clothes and at the same time agitating the clothes in the water. Upon 70 the upward movement of the agitator a partial vacuum or suction is created beneath the hood or cup of the agitator, drawing the water upwardly through the clothes disposed therebeneath. This forced passage of 75 the water and air through the clothes effectively removes therefrom all foreign substances without in the least damaging the fabric. Moreover, the arrangement of the plate 16 above the sloping walls of the hood 80 or cup 15, provides means for causing the movement of volumes of water in lateral and oblique directions. Upon the downward movement of the agitator the water and clothes disposed in the space between the 85 outer edge of the hood and the sides of the tub are drawn toward the agitator and away from the corrugated walls of the tub, the clothes coming in frictional contact with said corrugations thereby effecting a rubbing 90 action thereon. When the agitator is moved upwardly the volume of water and clothes about the hood are impelled outwardly against the sides of the tub again coming in frictional contact with the corrugations 95 on the tub. Thus the entire contents of the tub comes under the influence of the action of the agitator, so that by the joint action of frictional rubbing against the bottom and side walls of the tub and the rapid passage 100 of volumes of water through the clothes in both directions as thorough cleansing of all of the clothes contained in the tub will be readily effected and the degree of cleansing will be substantially uniform throughout 105 the entire mass of clothes.

The mechanism for reciprocating the agitator shaft comprises a hand lever made in two sections, the upper section 20 being detachably connected to the lower section 21 110 by bolting it to an angle portion 22 of the lower section by a bolt 23; the lower section of said hand operating lever is pivoted above its end at 24 on a bracket 24^a supported by the side of the tub. The lower end of the operating lever is connected to a swinging lever 25 pivotally supported at its upper end at 26 to a bracket 27 mounted on the side of the tub near the upper edge thereof, by a link 28 which has pivot connection 29 115 with the lower end of the operating lever at one end and pivot connection 30 at the other end with the swinging lever 25. The pivot connection 30 may be made adjustable so that it may be adjusted longitudinally of the swinging lever 25 thereby effecting an adjustment of the leverage. A link 31 is pivotally connected at 32 to the free end of the lever 25; said link at the opposite end being pivotally and eccentrically connected 120

at 33 to a large gear wheel 34. The gear wheel 34 is mounted on a shaft 35 which is revolvably supported in a bracket 36. The bracket 36 is attached to the bottom of the tub adjacent to the edge thereof, and is provided with an extending portion 37 in which is secured an outwardly extending stud or shaft 38. A balance wheel 39 is mounted on the stud 38 and has formed integral therewith a hub element 40 which carries a small pinion 41 which meshes with the large gear wheel 34. The bracket 36 is also provided with a bearing block 42 in which is journaled the inner end of the shaft 35. The shaft 35 carries near its inner end a pinion 43. A counter-shaft 44 is revolvably mounted below the shaft 35 and is supported at each end in bearings 45 and 46, respectively. The bearing 45 is formed in a downwardly extended portion of the bracket 36 and the bearing 46 is formed in a yoke portion 47 of a ribbed plate 48 which extends inwardly to the center of the bottom of the tub. It will be understood that the preferable construction is that shown in the drawings in which the bracket 36, the extending portion 37, the bearing 42, the plate 48, the yoke 47 and the bracket 8 are all made in one integral casting, although it will of course be apparent that these parts may be made in separate castings if desired.

The counter-shaft 44 has rigidly mounted thereon a pinion 49 which is adapted to mesh with the gear 43 whereby the shaft 44 is driven. The inner end of the shaft 44 has attached thereto a crank arm 50 the free end of which is adapted to engage in an oblong slot or race-way 51 formed in a plate 52. The plate 52 carries on its rearward face a boss 53 which is provided with an opening through which the agitator shaft extends. A set screw 54 threaded into the boss 53 provides means for detachably and adjustably connecting the plate 52 to the agitator shaft 7. By reference to Fig. 4 of the drawings it will be noted that the rearward face of the plate 52 engages against and slides upon the arms of the bracket 8 at points adjacent to each of the respective ends of said plate. This arrangement provides means for preventing the turning of the agitating shaft and keeping the parts in proper operative adjustment.

It will be observed that by mounting the driving mechanism below the tub the entire upper part of the machine is free from any permanently fixed obstructions so that the entire cover may be raised from the tub, permitting a hood of a relatively large diameter being adjusted upon the agitator shaft. Moreover, the fact that the driving mechanism is placed in a position below the tub adds to the safety of the machine for the reason that the exposed gearing and associated parts is in a position to prevent the

injury to unskilled operatives. In washing machines of the overhead drive type the liability of the hands of the operator coming in contact with the drive mechanism has lessened to a considerable extent their commercial practicability and utility. This disadvantage has been overcome, or at least greatly minimized, by the present construction.

From the foregoing description of the mechanism for operating the agitator shaft it will be understood that by the reciprocation of the operating lever, the swinging lever 25 is operated and that the force from the lower end of stud lever is imparted to the link 31 which rotates the gear 34, the gear 34 being entrained with the balance wheel provides for balancing the operation of the actuating mechanism. The balance wheel after the operation of the mechanism has been initiated assists in carrying the gear over dead center and minimizing to a considerable extent, the amount of power applied to the operating lever requisite for the operation of the driving mechanism. The rotation imparted to the shaft 35 by the actuation of the gear 34 is transmitted to the shaft 44 by the speed-increasing gearing, comprising the gear 43 and the pinion 49. It is obvious that the rotation of the shaft 44 operating the crank arm 50 imparts to the agitator shaft a vertical reciprocatory movement as the free end of the crank arm travels in its race-way 51, thus imparting to the agitator a rapid reciprocating motion in an up and down path of movement.

While I have illustrated and described my invention as embodied in a washing machine it is obvious that other uses may be made of the mechanism where the end to be attained is the rapid agitation of liquid in a container. It will also be obvious that details of construction may be changed within equivalent limits and I do not restrict myself, therefore, either to the embodiment of my invention in a washing machine or to specific features of construction that I have illustrated and described for the purposes of the present disclosure, but

What I claim and desire to secure by Letters Patent is.

1. The combination with a support, and a shaft mounted therein, of mechanism for imparting to said shaft a vertical reciprocating motion comprising a lever fulcrumed to said support, a second lever connected with said first-named lever, a large gear wheel linked to the lower end of said second-named lever, a balance wheel entrained with said gear wheel, a shaft driven by said gear wheel, a second shaft entrained with said first-named shaft by a speed increasing gearing, a crank arm driven by said second-named shaft, and a connection between said

crank arm and said shaft, substantially as specified.

2. The combination with a support, of a lever pivoted thereto, an operating lever 5 connected to said first-named lever, a large gear wheel linked to one end of said first-named lever, a balance wheel carried by said support, a speed increasing connection between said gear wheel and said balance 10 wheel, a shaft driven by said large gear wheel, a second shaft entrained with said first-named shaft, and a vertically disposed shaft operatively connected to said last-named shaft for imparting an alternating 15 vertical movement thereto from the continuous rotary motion of said second-named shaft, substantially as specified.

3. The combination with a support, of a horizontally disposed driven shaft, a lever 20 pivoted to said support, power connections between said lever and said shaft whereby said shaft is rotated continuously in one direction by oscillation of said lever, a second horizontal shaft entrained with said 25 first-named shaft by speed increasing gearing, a balance wheel, gearing entraining said balance wheel with one of said shafts, a crank arm operated by said second shaft, a vertical shaft, and a connection between 30 said crank arm and said vertical shaft whereby said vertical shaft is caused to reciprocate in an up and down path of movement.

4. The combination with a support, a 35 lever of the first class pivoted to said support, a lever of the third class pivoted to said support, a link operatively connecting said levers, a gear wheel, a link operatively connecting said second-named lever with 40 said gear wheel, a balance wheel entrained with said gear wheel, a shaft driven by said gear wheel, a vertically disposed shaft, and connections between said driven shaft and said vertically disposed shaft whereby an 45 alternating motion in a vertical path is imparted to the latter by a continuous rotary motion of the former, substantially as specified.

5. In a machine of the character 50 described, a support, a hollow standard attached to one side of said support, a shaft extending through said support and through said hollow standard, a mechanism mounted on said shaft on the same side of said support with said standard, a drive shaft 55 mounted below said support, means for rotating said last-named shaft, speed increasing transmission devices driven by said drive shaft, and means driven by said 60 transmission devices for reciprocating said first-named shaft longitudinally effectively to actuate said mechanism, by the continuous rotation of said second-named shaft in one direction.

6. In a machine of the character de-

scribed, the combination with a support, a shaft extending above and below said support, a mechanism carried by said shaft above said support, means above and below said support for guiding said shaft in its 70 movements, a revoluble shaft carried below said support, a connection between said revoluble shaft and said first-named shaft for imparting a vertical reciprocating movement to said first-named shaft by the continuous rotation of said revoluble shaft in one direction, a gear wheel, a lever, link connections whereby oscillation of said lever will rotate said gear wheel in either direction as desired, and means for driving said 80 revoluble shaft from said gear wheel.

7. In a machine of the character described, a support, a lever pivoted to said support, a second lever pivoted to said support, a link connecting one end of said first- 85 named lever with said second-named lever, a gear wheel, a link connecting said second lever with said gear wheel, a shaft, means driven by said gear wheel for revolving said shaft, a vertical shaft, guides in which said 90 vertical shaft is movable, a mechanism controlled by said vertical shaft, and crank connections between said vertical shaft and said first-named shaft whereby said vertical shaft will be reciprocated longitudinally by 95 the continuous rotation of said first-named shaft in either direction.

8. The combination with a support, a lever of the first class pivoted to said support, a large gear wheel, means for revolving 100 said gear wheel by said lever, a balance wheel entrained with said gear wheel, a shaft driven by said gear wheel, a crank device, speed-increasing gearing for driving said crank device from said shaft and at 105 relatively greater speed than said shaft, a hollow standard, a vertical shaft operatively mounted in said standard, and means for imparting an alternating vertical motion to said vertical shaft from said crank device 110 by the continuous rotation of said first-named shaft in one direction.

9. The combination with a support of a horizontal shaft, a vertical lever of the first class pivoted to said support, mechanism 115 for imparting a continuous rotary motion to said shaft by operation of said lever, a balance wheel entrained with said shaft, a second shaft entrained with said first-named shaft by speed-increasing gearing, a crank 120 arm operated by said second shaft, a hollow vertical standard and a connection between said crank arm and said vertical shaft, whereby said vertical shaft is reciprocated vertically by the continuous rotation of said 125 first-named shaft in one direction.

10. The combination of a support, a lever pivoted to said support, an additional lever pivoted to said support, a link connecting said two levers, a gear wheel, a link connect- 130

ing one of said levers with said gear wheel, a balance wheel, a horizontal shaft driven by said gear wheel, an additional shaft driven by said horizontal shaft, a vertical shaft and connections driven by said additional shaft for reciprocating said vertical shaft vertically by operation of said additional shaft.

In witness whereof, I have signed this specification in the presence of two subscribing witnesses.

CHARLES J. MARTH.
